WATER CIRCULATING PUMP

Eugene G. Danner, 9122 71st Road,
Forest Hills, N.Y. 11375

Filed Nov. 3, 1970, Ser. No. 25,801

Term of patent 14 years

Int. Cl. D15—02

U.S. Cl. D65—1 R

FIG. I

Des. 226,134

PAGE 2

FIG. II

FIG. III

FIG. IVFIG. I is a perspective view of the water circulating pump, showing my new design;

FIG. II is an elevation view of the back thereof;

FIG. III is an elevation view of the side thereof; and

FIG. IV is a perspective view from the direction opposite that of FIG. I.

I claim:

The ornamental design for a water circulating pump, as shown and described.
